DESIGN FOR A TABLE LIGHTER FOR CIGARETTES OR THE LIKE

Irving Florman, New York, N. Y.

Application March 3, 1943, Serial No. 109,650

Term of patent 14 years

To all whom it may concern:

Be it known that I, Irving Florman, a citizen of the United States, residing at New York, in the county of New York and State of New York, have invented a new, original, and ornamental Design for a Table Lighter for Cigarettes or the like, of which the following is a specification, reference being made to the accompanying drawing, forming a part thereof.

I claim:

The ornamental design for a table lighter for cigarettes or the like, substantially as shown.

IRVING FLORMAN.
